(57) **CLAIM**

The ornamental design for a headgear clip for patient interface, as shown and described.

DESCRIPTION

FIG. 1 is a top front perspective view of a headgear clip for patient interface according to our new ornamental design in a state of use;

FIG. 2 is another top front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and

FIG. 9 is a rear perspective view thereof.

FIG. 10 is a perspective view of a headgear clip for patient interface showing a second embodiment according to our new ornamental design;

FIG. 11 is an enlarged perspective view thereof in isolation;

FIG. 12 is a front view thereof;

FIG. 13 is a rear view thereof;

FIG. 14 is a right side view thereof;

FIG. 15 is a left side view thereof;

FIG. 16 is a top view thereof;

FIG. 17 is a bottom view thereof; and,

FIG. 18 is another perspective view thereof.

(Continued)

The broken lines in the drawings depict environmental subject matter and form no part of the claimed design.
